UNITED STATES PATENT OFFICE.

CLIFTON H. WHEELER AND JOSEPH J. MULLAN, OF PHILADELPHIA, PENNSYLVANIA, ASSIGNORS, BY MESNE ASSIGNMENTS, TO C. H. WHEELER MANUFACTURING COMPANY, OF PHILADELPHIA, PENNSYLVANIA, A CORPORATION OF PENNSYLVANIA.

CONDENSER.

No. 817,458.

Specification of Letters Patent.

Patented April 10, 1906.

Application filed August 4, 1905. Serial No. 272,624.

To all whom it may concern:

Be it known that we, CLIFTON H. WHEELER and JOSEPH J. MULLAN, citizens of the United States, residing at Philadelphia, in the county of Philadelphia and State of Pennsylvania, have invented a new and useful Improvement in Condensers, of which the following is a specification.

The object of our invention is not only to completely convert the spent steam or water of condensation into liquid form, but to maintain the same at such a high temperature as to be able to reconvert the same into steam both with the expenditure of the smallest consistent number of units of heat and as quickly as possible, or, in other words, to retain all the heat possible in the liquid, and so effect economy in the operation of the steam plant. To effect this result and in carrying out our invention, the spent steam or water of condensation as it enters the condenser comes in contact with a bank of tubes containing a cooling liquid at its lowest temperature, and the temperature of this liquid is increased by taking up heat and that of the water of condensation considerably reduced. This liquid then passes to a bank of tubes at a lower level and the water of condensation falling strikes these latter tubes, is completely liquefied, and in being cooled further increases the temperature of the liquid in the tubes. The liquid in the second bank of tubes then passes to a bank of tubes at a lower level and the condensed liquid still falling and cooling strikes the third bank of tubes, in which the liquid is very much hotter than when it left the first bank of tubes, and in so doing its temperature is raised, thereby avoiding all risk or liability of refrigeration, and thus preparing the liquid to return hot to the boiler, where less units of heat are expended to reconvert the same into steam.

The condenser is constructed with a horizontal cylindrical portion having these three banks of tubes, and the ends of the condenser are alike, but reversed, and of such peculiar construction that the cooling liquid entering one end is first taken around through an outer compartment and then enters an internal compartment and the higher bank of tubes, and before leaving the other end of the condenser it passes around through a similar

outer compartment having a perceptible radiating-surface.

In the drawings, Figure 1 is a vertical longitudinal section, Fig. 2 a plan, and Fig. 3 a cross-section and elevation at the dotted line $x x$ of Fig. 1.

The cylindrical body a of the condenser is provided with heads a' , with the inlet-pipe b in the top for the water of condensation and the exit-pipe c in the bottom for the feed-water and with a baffle-plate d within the cylindrical body below the opening of the inlet-pipe b and against which the entering water of condensation strikes and is dispersed. Within this cylindrical body and extending from end to end through the heads a' are the banks of horizontal tubes e, f , and g . The ends of the condenser, which are made alike, but reversed, are represented at h and i . The end h is provided with an aperture 2 , to which is connected an inlet-pipe k . This end h is provided with an annular compartment h' between concentric walls and with an opening 3 in the inner wall at the top. Said end is also provided with a partition h^2 , dividing the inner portion of the end up into compartments h^3 and h^4 . The opening 3 forms an entrance to the compartment h^3 and one end of the bank of tubes e opens into this compartment. The compartment h^4 of this end is larger and the banks of tubes f, g open into the same. The end i , like the end h , but reversed, is also provided with an aperture 2 and the opening 3 with the pipe l , connecting the part of the end at the aperture 2 with an annular compartment i' , formed between concentric walls with a partition i^2 and compartments i^3, i^4 . The opposite ends of the banks of tubes e and f open into the compartment i^4 , and the opposite ends of the bank of tubes g open into the compartment i^3 .

In the operation of the condenser the cooling-water enters the end h by the pipe k , passes through the aperture 2 and around through the annular compartment h' , through the opening 3 into the compartment h^3 , then entirely through the bank of tubes e and into the compartment i^4 of the end i . Turning, the water enters and passes entirely through the bank of tubes f and into the compartment h^4 of the end h , and turning there the water enters and passes entirely through

the bank of tubes *g* into the compartment *i*³ of the end *i*. From there the water passes by opening 3 into the annular compartment *i'*, and so around the end *i* and discharges by 5 the aperture 2 and the pipe *l*.

From the illustration and foregoing description it will be apparent that the annular or outer compartments of the condenser ends are of appreciably greater diameter than the 10 inner compartments thereof, which embrace or encompass the ends of the series of tubes, and consequently it will be manifest that inasmuch as the circulating water or cooling liquid is compelled to pass through the annular compartment at the inlet end before reaching the water-chamber or inner compartment and to pass from the water-chamber in the opposite end to the annular compartment in that end to the outlet-pipe on the top thereof 15 20 25 30 35 40 45 50 55 60 65 70 75 80 85 90 95 100 105 110 115 120 125 130

that all the tubes in the condenser will be entirely below the level of the water in the ends at all times during the working of the apparatus, insuring the tubes being full, which is the primary object of the construction disclosed, and in reality the most important part of our invention. Moreover, it will be understood that the circulating water may be passed through the series of any odd number of courses each consisting of a bank of tubes within the condenser without departing from the nature and spirit of our invention. Meanwhile the condensing steam or the water of condensation from the engines enters the cylindrical body of the condenser by pipe *b* and striking the baffle-plate is dispersed over the surface of the bank of tubes *e*, and as this condensing steam is very hot and the water in the bank of tubes *e* at its lowest temperature the effect is a considerable condensation of the exhaust-steam. This exhaust-steam passes through between the tubes of the bank *e* and falls upon the tubes of the bank *f*, the water in the bank of tubes *e* meanwhile taking up considerable 40 45 50 55 60 65 70 75 80 85 90 95 100 105 110 115 120 125 130

heat in reducing the temperature of the water of condensation. Consequently the water in the tubes *f* is hotter than the water in the tubes *e*, but is yet sufficiently cool to exert its heat effect in completely condensing the steam as the same passes over the tubes of the bank *f*. At this point the spent steam is presumed to be completely condensed and liquefied, the heat having been taken out of it by the water in the bank of tubes *f*, the heat of which is materially increased. As the condensed steam or liquid, which it now is, passes farther down in the cylindrical body of the condenser it strikes the bank of tubes *g*. At this point the temperature of this liquid is presumed to be lower than the temperature of the water in the pipes *g*. Consequently this liquid takes up some of the heat—that is, a small or appreciable amount from the liquid in the tubes *g*, and the water finally 55 60 65 70 75 80 85 90 95 100 105 110 115 120 125 130

flows by gravity by the exit-pipe *c* and re-

turns to the boiler as feed-water. The heated water in the bank of tubes *g* as it passes through the annular compartment *i'* of the condenser end *i* is appreciably cooled, and from the outlet-pipe this water is presumed to pass to a suitable cooling-tower in which the same is cooled before it returns to repeat its work by passing into the condenser through the annular pipe *h* and repeating the operation. 70 75 80 85 90 95 100 105 110 115 120 125 130

By this apparatus we are enabled to quickly and effectively condense the spent steam from the engines using the same, and it not only fully condenses the same into feed-water, but maintains said feed-water at a reasonably high temperature, so that when the same returns to the boiler as feed-water it will not require a large number of units of heat to reconvert the same into steam, and at the same time the condenser is so constructed that cooling-water entering the same is effective in contact with the hottest entering spent steam for effecting a large reduction in the temperature therefor. The movement of the cooling-water so progresses as to completely condense the spent steam and at the same time to give off part of its surplus heat to maintain the water of condensation as feed-water at as high a temperature as possible, and this cooling-water has a part of its temperature reduced by passing through the annular compartment in the second end of the condenser before passing away to a cooling-tower to be cooled preparatory to repeating the operation. 80 85 90 95 100 105 110 115 120 125 130

We claim as our invention—

1. The combination with a cylindrical body and heads therefor, of series or banks of tubes extending through the cylindrical body and said heads, ends to the cylindrical body that are alike but reversed, and so arranged that the passage of cooling liquid is progressive through the series of tubes, and means forming part of said ends whereby the water in the ends is at a higher level than the water in the tubes. 105 110 115 120 125 130

2. In a condenser, an end comprising concentric walls forming an annular compartment, a partition dividing the interior into two compartments of varying sizes, an entrance opening into the annular compartment and an entrance opening from said compartment into one of the internal compartments. 115 120 125 130

3. In a condenser, an end comprising concentric walls forming an annular compartment, a partition dividing the interior into two compartments of varying sizes, and an entrance opening into the annular compartment and an entrance opening from said compartment into one of the internal compartments in combination with three banks of tubes, the one entering the smaller compartment of the end and the other two the larger compartment. 120 125 130

4. In a condenser the combination with a 130

cylindrical body having an inlet-pipe for the spent steam and water of condensation and an exit-pipe for the feed-water, of ends connected to the cylindrical body that are alike but reversed, each end comprising concentric walls forming between them an annular compartment with an opening to this annular compartment, a partition dividing the interior into two compartments of different sizes with an opening from the annular compartment to the smaller of these interior compartments, three series of banks of tubes passing through the cylindrical body of the condenser, one of said banks opening into the 15 smaller interior compartments of the ends and the other two opening into the larger interior compartments of the ends.

5. In a condenser, the combination with several independent horizontally-disposed 20 series or banks of tubes, of cylindrical ends providing means for conveying and circulating the cooling-water first through the higher bank of tubes, then through the intermediate bank of tubes and finally through the 25 lower bank of tubes, and means forming part of said ends whereby the water in the ends is maintained at a higher level than the water in the tubes.

6. In a condenser the combination with 30 several independent series or banks of tubes, of cylinder ends providing means for conveying and circulating cooling-water first around and within the shell of one end and into a small internal compartment, thence through 35 the higher of the bank of tubes, and into a large internal compartment of the other cylinder end and through the intermediate bank of tubes into a large compartment of the first end, thence into the lower of the bank of 40 tubes and into the smaller internal compartment of the second end, thence around and within the shell of said end and away.

7. A surface condenser comprising a horizontally-placed condenser-body, heads for 45 the same, tubes passing through said body and heads, ends for the said heads, and means forming part of said ends whereby the water in the ends is maintained at a higher level than the water in the tubes.

50 8. A surface condenser comprising a condenser-body, heads for the same, tubes passing through said body and heads, ends for the said heads, an internal wall in each of said heads conforming in outline therewith and 55 providing a compartment between the same and the exterior wall of the end, an opening being provided in the exterior wall of each end and leading to the said compartment therein, and another opening provided in the 60 interior wall of each end at the side opposite the

aforesaid opening and leading from the said compartment to the interior chamber of the end.

9. In a condenser, the combination with a condenser and body, a series of tubes through 65 the same, and heads therefor, of ends to the body that are alike, and each end comprising a wall surrounding the tubes at one end and forming a compartment, and a wall outside of appreciably greater diameter than the 70 aforesaid wall, inclosing an outer compartment which with the inner compartment and tubes is filled at all times with the cooling liquid whereby the water-level in the ends is higher than in the tubes, insuring the tubes 75 being full.

10. In a condenser, ends that are alike but reversed, and each end comprising inner and outer walls providing concentric compartments with an entrance opening into the 80 outer compartment, and an opening providing communication between the respective compartments at the side opposite the aforesaid entrance-opening.

11. A surface condenser comprising a condenser-body, heads for the same, tubes passing through said body and heads, ends for the said heads, means forming part of said ends whereby the water-level in the ends is higher than in the tubes, insuring the tubes being 85 full, and means contained within the aforesaid means forming part of said ends for dividing the tubes in the condenser into series of courses through which the cooling liquid 90 is compelled to flow.

95 12. A surface condenser comprising a condenser-body, heads for the same, tubes passing through said body and heads, ends for the said heads, an internal wall in each of said heads conforming in outline therewith 100 and providing a compartment between the same and the exterior wall of the end, an opening being provided in the exterior wall of each end and leading to the said compartment therein, and another opening provided 105 in the interior wall of each end at the side opposite the aforesaid opening and leading from the said compartment to the interior chamber of the end, and means contained within the inner chambers of the said ends dividing 110 the tubes in the condenser into series of courses through which the cooling liquid is compelled to flow.

Signed by us this 26th day of July, 1905.
